UNITED STATES PATENT OFFICE.

MARGARET B. GOODWIN, OF DENVER, COLORADO.

DESIGN FOR A FOOT-REST FOR RADIATORS AND REGISTERS.

43,274.

Specification for Design.

Patented Nov. 26, 1912.

Application filed December 16, 1911. Serial No. 666,269. Term of patent 7 years.

To all whom it may concern:

Be it known that I, MARGARET B. GOODWIN, a citizen of the United States of America, residing at the city and county of Denver and State of Colorado, have invented a new, original, and ornamental Design for a Foot-Rest for Radiators and Registers, of which the following is a specification, reference being had to the accompanying drawing, forming part thereof.

The figure is a perspective view of a foot rest for radiators and registers, used in con-

nection with the heating systems of residences and other buildings, showing my new design.

I claim:

The ornamental design for a foot rest for radiators and registers, as shown.

In testimony whereof I affix my signature in presence of two witnesses.

MARGARET B. GOODWIN.
